UNITED STATES PATENT OFFICE.

HOYT L. CONARY, OF WALTHAM, MASSACHUSETTS.

FENDER FOR ELEVATORS.

SPECIFICATION forming part of Letters Patent No. 748,702, dated January 5, 1904.

Application filed December 12, 1902. Serial No. 134,958. (No model.)

To all whom it may concern:

Be it known that I, HOYT L. CONARY, a citizen of the United States, and a resident of Waltham, in the county of Middlesex and 5 State of Massachusetts, have invented new and useful Improvements in Fenders for Elevators, of which the following is a specification.

My invention relates to safety appliances for elevators, and has for its object to provide a fender for elevators which will add to the safety of persons using the latter.

Many accidents occur in the operation of elevators through the carelessness or inadvertence of persons standing on landings with 15 part of their body—as, for example, their foot—projecting into the elevator-well and into the path of the elevator when the latter is descending. Oftentimes also through the carelessness of the operator of the elevator 20 the door to the well is opened before the car in descending has reached the level of the landing, and under such circumstances it has frequently happened that persons waiting on the landing have without observing the 25 position of the car with due care stepped forward when the door was opened, so as to place their foot or other part of their body in the path of the car, with injury to that person as the result. My fender is designed to prevent 30 persons being injured under such circumstances.

My invention resides in the combination, with an elevator-car, of a fender movably mounted on the car, so that when engaged by 35 a projecting body on a landing or other fixed point it is moved in line with the wall of the car and by that movement throws the body to one side out of the path of the car.

In the best form of my invention the fender is arranged below the car and comprises a swinging frame pivoted to the car, so that when the car is descending and the fender strikes a body projecting from a landing or other support the fender is swung on the 45 pivot toward one side of the car, carrying the body with it out of the path of the car. Herein I have utilized the weight of the fender at one side of the pivot to hold the fender in normal position, and as in practice it is desirable that the instrument be quite sensitive, owing to the dependence for its action upon its frictional engagement with the object in its

path, I preferably provide a weight or its equivalent upon the opposite side of the pivot to counterbalance part, but not all, of the 55 weight of the fender.

In the accompanying drawings, which show an embodiment of my invention, Figure 1 is an elevation, partly in section, of portions of an elevator car and well embodying the preferred form of my invention. Fig. 2 is a plan view of the fender detached. Fig. 3 shows the operation of the fender.

Having reference to the drawings, 1 represents one side of an elevator-well, and 2 a 65 landing. Within the well is shown a portion of an elevator-car 3, the doorway of which is shown at 4.

Upon the under side of the floor 41 of the car 3 adjacent the entrance 4 is fastened a 70 pair of brackets 5, in which is journaled the ends of a bar 6. Fast on the bar 6 is a frame 7, carrying on one side of bar 6 a curved plate 8, and provided at the opposite side of bar 6 is a pair of arms 9, on each of which is 75 fixed an adjustable weight 10. The purpose of the weights 10 is to nearly but not quite counterbalance the weight of frame 7 and plate 8, the slight preponderance in weight of the frame and plate at that side of bar 6 80 acting to hold said parts normally at their lowest point, with plate 8 below the sill 11 of the entrance 4 and with the arms 71 of frame 7 against the under side of the floor 41 of the car, which serves to limit the extent of downward movement of plate 8.

When car 3 in descending carries plate 8 against an object on the landing 2 and projecting into the elevator-well, as indicated at 12, the frictional contact of that object with 90 the plate 8 arrests the downward travel of the plate and causes it and frame 7 to swing upwardly relatively to car 3 on the axis of bar 6. This relative movement between car 3 and frame 7 carries plate 8 out from beneath and to one side of car 3, (see Fig. 3,) and inasmuch as the axis of bar 6 travels vertically in a straight line 13 13 it follows that the resulting force applied to the object 12 through frame 7 and plate 8 is on a line 100 substantially parallel with landing 2 or, in other words, crosswise of line 13 13, so that the object 12 is slid on landing 2 back out of the path of and to one side of the elevator.

car. In other words, I have by the interposition of mechanism transformed the dangerous vertical motion of the elevator-car into a beneficial horizontal motion which 5 pushes harmlessly out of the path of the elevator any object in its path.

Guards have heretofore been applied to elevators which consisted of a plate depending from and fast to the sill of the car and of 10 such length that before the car in descending approached a landing near enough for the operator of the car to reach and open the well-door the lower end of the guard had passed the landing, so that when the door 15 was opened, even though the car was still above the landing, the space between the bottom of the car and the landing was closed by the guard. The objections to such devices, however, are that they are useless on 20 elevators where there are no well-doors and in cases where the well-doors are left open either purposely or inadvertently, for there is obviously as much danger to the person from the lower edge of the guard as there is 25 from the unguarded lower edge of the car. On the other hand, my fender is useful on elevators of all kinds, and I have found from practice that it fully meets all the requirements essential to an elevator appliance for 30 serving the purpose for which it is designed.

I claim—

1. The combination with an elevator-car, of a fender carried by said car and movable to a position in line with the wall of the car, and 35 means for supporting said fender on said car in such manner as to permit the fender to move automatically when struck by an object in the path of the car and shove the object out of range of the moving car.
2. The combination with an elevator-car, of 40 a fender carried by said car and movable to a position in line with the wall of the car, and means for pivotally supporting said fender on said car in such manner as to permit the fender to rock automatically on its pivotal sup-

port when struck by an object in the path of the car and shove the object out of range of the moving car.

3. The combination with an elevator-car, of a fender carried by said car and movable to 50 a position in line with the wall of the car, and means for supporting said fender below the floor of the car in such manner as to permit the fender to move automatically when struck by an object in the path of the car and shove 55 the object out of range of the moving car.

4. The combination with an elevator-car, of a fender carried by said car and movable to 60 a position in line with the wall of the car, and means for pivotally supporting the said fender below the floor of the car in such manner as to permit the fender to rock automatically on its pivotal support when struck by an object 65 in the path of the car and shove the object out of range of the moving car.

5. The combination with an elevator-car, of a movable fender below the floor of the car adapted to be swung into line with the front wall of the car when the surface of the fender 70 engages an object projecting into the path of the car.

6. The combination with an elevator-car, of a pivoted, counterbalanced fender below the floor of the car adapted to be swung by contact with an object in the path of the car into 75 line with the front wall of the car.

7. The combination with an elevator-car, of a fender supported on said car in such manner as to be automatically movable to a position in line with the wall of the car when 80 struck by an object in the path of the car, said fender having an inclined face to shove the object out of range of the moving car.

Signed by me, at Boston, Massachusetts, this 10th day of December, 1902.

HOYT L. CONARY.
